UNITED STATES PATENT OFFICE.

EDWIN J. HAYDEN AND JOHN R. GORDON, OF MINNEAPOLIS, MINNESOTA.

SUSPENDERS.

979,947.

Specification of Letters Patent. Patented Dec. 27, 1910.

Application filed November 10, 1909. Serial No. 527,256.

To all whom it may concern:

Be it known that we, EDWIN J. HAYDEN and JOHN R. GORDON, citizens of the United States, residing at Minneapolis, in the county 5 of Hennepin and State of Minnesota, have invented new and useful Improvements in Suspenders, of which the following is a specification.

Our invention relates to certain new and 10 useful improvements in suspenders and it consists in the novel combination and arrangement of parts as will be hereinafter more particularly described and ascertained in and by the following claim.

15 In the drawings, Figure 1 is a plan view of our complete invention showing a portion thereof in a detached position. Fig. 2 is a vertical longitudinal section taken on the line 4—4 of Fig. 1. Fig. 3 is a perspective view 20 of a plate which we employ in connection with the several parts of the suspenders for adjusting the buttoning straps on either end of the suspenders.

25 Referring to the drawings 1 represents the sliding connection for connecting the several portions comprising the suspenders and is located at the back of the wearer adjacent to or at a suitable distance above the buttoning end of the same. The connecting 30 portion 1 is composed of a central elongated link 2, to which is attached, along its opposite longitudinal portions plates 3, a portion of which are approximately of the same length as the longitudinal portions of said 35 link for holding the plates in rigid connection with the link thus formed, the said plates having extensions 4 which are narrower than the remaining portions and looped to freely receive two oppositely 40 located links 5, the latter being approximately the same length as the central link 2, whereby the links are susceptible to a transverse and independent movement in respect to the central link 2 yet permitting the said 45 links to turn independently of one another. The rear buttoning straps 6 are similarly constructed, one end of one of said straps being passed through the central loop 2 and having its terminal end sewed to or otherwise 50 attached to the opposite strap forming a sliding loop 7 and the end of the opposite

strap is passed through the lower link 5 of the sliding connection and attached to the other strap forming a loop 7, whereby a sliding connection is made for the buttoning 55 straps in respect to the loop and link referred to.

The shoulder bands at one end pass through the upper link 5 and at their opposite ends are attached to one end of a 60 strap 10 at a point 11, the lower ends of said straps being secured in any suitable and mechanical manner to the lower ends of said shoulder bands, and fixed to the straps 10 adjacent to the lower ends thereof are snap 65 buttons 12 which are adapted to be received by the catch or snap eyelets 13 formed in the plates 14, after the buttoning loops 15' have been placed in their proper position as clearly shown in Fig. 2. The plates 14 are 70 provided with oppositely located slots 15 on either side of the snap opening or eyelet formed therein, said slots being formed by a suitable die or other means whereby outwardly projecting elongated frictional edges 75 16 are formed for the purpose hereinafter to be described. The straps 10 are passed through the slots 15 of the plates 14 in the manner as clearly shown in Fig. 2, in which instance the straps will bear directly upon 80 the elongated frictional edges 16 of the plates 14, thereby bringing the parts in a binding or frictional contact with one another when strain is brought to bear upon the buttoning loops 15', but when said strain 85 is released the plates may be adjusted in any position along the length of the straps 10 for holding the buttoning loops 15' in their proper or desired position in respect to the shoulder bands of the suspenders. 90

Having thus fully described the invention what is claimed as new is:

A suspender comprising a shoulder band, a strap, one end of which is secured to said band at a suitable distance along its length 95 and having its opposite end also attached to the lower end of the band, a plane oblong plate upon said strap having elongated openings adjacent to its opposite ends through which the strap freely passes, said plate 100 being provided on one face and at the inner sides of said slots with flanges projecting at

right angles to one face of the plate, the ends of said flanges frictionally binding on the strap when strain is brought to bear upon the latter and a snap button secured to the strap adjacent to the lower end thereof, and adapted to be received by the snap opening formed in the plate, as and for the purpose described.

In testimony whereof we affix our signatures in presence of two witnesses.

EDWIN J. HAYDEN.
JOHN R. GORDON.
